UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

INSOLE.

1,109,760.

Specification of Letters Patent.

Patented Sept. 8, 1914.

Application filed January 3, 1912. Serial No. 569,225.

To all whom it may concern:

Be it known that I, ALBERT E. JOHNSON, a citizen of the United States, residing at Beverly, in the county of Essex and State of Massachusetts, have invented certain new and useful Improvements in Insoles; and I do hereby declare the following to be a full, clear, and exact description of the invention, such as will enable others skilled in the art to which it appertains to make and use the same.

This invention relates to an improvement in insoles for use in the manufacture of welt shoes, and more particularly to that class of reinforced insoles known as "Economy" insoles, the single lipped type of which is illustrated and described in the present inventor's United States Letters Patent No. 656,842, dated August 28, 1900, and the double lipped type of which is illustrated and described in the present inventor's United States Letters Patent No. 849,245, dated April 2, 1907. The single lipped type is prepared for reinforcing, that is, the operation of applying the reinforce to the insole, from a sole shaped blank, by cutting one face of the blank within its edge to form a flap parallel to the edge. The flap is turned up at right angles to the cut face of the blank to form an upright rib along the shank and forepart of the insole. As thus prepared, a sheet of reinforcing material is stuck roughly on the blank and the blank and sheet are then passed through a reinforcing machine. It was found, however, that a flap turned to the position shown in Letters Patent No. 656,842, has a tendency to droop toward its original position over the channel, especially when working the poorer grades of stock used for reinforced insoles. When this happened in preliminarily applying the sticky sheet of material to the sole, it adhered to the outer surface of the flap. Under such conditions the tools of the reinforcing machine are prevented from working the reinforce down into its proper position in the angle between the channel and the inner surface of the flap, as will readily be recognized by those skilled in the art. The double lipped type overcame the objection just referred to as the uniting of the flap to a marginal lip cut parallel thereto to hold it securely in its upright position, preventing an exposure of its outer sur-

face to the sticky surface of the reinforce, and permitting a proper action of the reinforcing machine on the sole. In this type after the flap and lip have been turned up at right angles to the lipped face of the blank they are united either by cement and pressure, or stitches. Substantially four steps are taken in preparing for reinforcing the double lipped type of insole described in said Letters Patent No. 849,245, namely; the step of edge slitting and channelling, the step of lip and flap turning, the step of cement applying, and the step of pressure applying. The use of cement adds materially to the cost of the insole and the operation of cement applying involves the use of special apparatus which must be carefully employed to prevent the smearing of the insole. In certain grades of the leather used, such as "splits", cement has been found to be ineffective to prevent a drooping or partial return of the flap to its position against the sole and for this reason a row of stitching is now generally used to secure the flap and lip together. This also involves the use of special machinery.

The object of the present invention is to produce a novel "Economy" insole, of either the single lipped or double lipped type which may be properly prepared for reinforcing in an economic manner. It will be obvious to those skilled in the art, however, that the invention is not limited in the scope of its application to the so-called "Economy" insole, but is equally useful in connection with any sole blank having a marginal lip or rib which should be permanently set in substantially upright position.

With this object in view a feature of the present invention contemplates the manufacture of an insole consisting of a body portion having a flap, formed by cutting a channel in one face of the sole downwardly and outwardly toward its margin, which is turned up and permanently set by molding pressure only in an upturned position in which its outer surface is not exposed to the sticky side of the reinforce. Such a position of the flap prevents a detrimental adherence of the reinforce to the flap and insures a successful operation of the reinforcing machine on the prepared sole. Broadly considered the flap may be set by molding pressure into any suitable form found desirable or expedient. In the preferred form of the invention, to

counteract the tendency of the flap to droop toward its original position over the channel, the flap is stiffened and held in its upturned position by transverse crimps or corrugations formed by the molding pressure. This manner of molding the flap so as to permanently set it forms an important feature of the present invention and is equally advantageous with either type of insole. In applying this feature of the invention to the double lipped type of insole the crimps, or corrugations, in the flap and lip coöperate with each other to unite these parts and thus produce from the two a single substantially upright rib to which the upper and welt may be secured.

This novel insole when provided with a flap and a lip, is prepared for reinforcing by channeling and edge slitting the blank in the usual way, then tempering the flap and lip thus produced, and then permanently setting the tempered parts in substantially upright position by molding coöoperating crimps or corrugations in the flap and lip.

In making shoes with pointed toes, especially in women's work using all leather insoles known as "solids," it is advantageous to turn up both the flap and the lip instead of leaving the flap lying in the channel as is usual to assist in feeding the shoe at the toe during the inseaming operation. The present invention is, therefore, useful in making "solids" as well as reinforced insoles, and while its preferred use is as a blank for reinforced insoles, as herein specifically described, it should be understood that the invention is not limited to such use.

In the accompanying drawings illustrating the improved double lipped "Economy" insole in the best form now known to the inventor, Figure 1 is a plan of the insole, the reinforcing material being omitted and the rib molding operation being only partially completed; Fig. 2 is a transverse section on the line 2—2 Fig. 1; Fig. 3 is a detail in right side elevation of the molded compound rib; and Fig. 4 illustrates the detrimental effect when the setting operation on the flap is ineffectively performed permitting the outer surface of the flap to become exposed.

Referring now to the form of the invention illustrated in the drawings, a sole shaped blank 1 is first passed through a channeling machine in which the edge of the blank is split along its shank and forepart to produce a lip 2 and a feather 3, and a channel is cut in one face of the blank downwardly and outwardly within the edge cut to produce a flap 4. If at this step in the manufacture of the insole the flap and lip are turned up and so left without uniting them in some manner, it is found that the flap will droop toward its original position over the channel. When the sheet of reinforcing material is applied roughly to the

blank, preliminary to passing the blank and sheet through a reinforcing machine, the exposed outer surface of the flap adheres to the sticky surface of the sheet as shown in Fig. 4. If the blank and sheet are then passed through the reinforcing machine it is obvious that the tools with which the machine is provided will not be able to draw the reinforcing material down into the angle between the channel and inner surface of the flap. Heretofore in order to prevent the drooping of the flap it has been necessary to unite the flap and lip by either cement and pressure, or by stitches.

In the illustrated embodiment of the invention the marginal portion of the blank which includes the flap and lip produced by the edge slitting and channeling operations is tempered. The tempered marginal portion of the blank is then passed through a molding machine provided with suitable tools, preferably rolls having corrugations formed upon their peripheries which mold the marginal portion of the blank and permanently set the flap and lip into substantially the form illustrated at the left in Figs. 1 and 2. These rolls form transverse crimps or corrugations in the flap 4 which stiffen the flap so that the drooping tendency of the flap is counteracted. The set imparted to the flap is such that there is no liability of the sheet of sticky reinforce adhering to the outer surface of the flap. By simultaneously turning, molding, and crimping the lip and flap these parts are united to form a single substantially upright rib. The union thus obtained is equally as effective as though either cement or stitches were used while all the disadvantages attendant upon the use of either of these uniting means are obviated.

As is well known to those skilled in the art, practical experience has shown that, in order to permanently set the rib, something more than a mere pressure on the rib is required. It has been the practice heretofore, after channeling the insole blanks, to turn up the lip or lips forming the rib, by hammers, rotary lip-turning tools, or other means, using pressure alone. This operation does not effectually counteract the tendency of the lip, or lips, to droop or fall back toward the face of the insole, resulting in crippled insoles as hereinbefore described.

I have discovered that the permanent set, hereinbefore referred to, of the flap is obtained by a stretching of the fibers of the leather at its upper up-turned margin. In accordance with my invention, the fibers are so stretched that the length of the up-turned edge of the flap is greater than the length at its base, which, as will be recognized by those skilled in the art, causes a stiffening of the flap, as hereinbefore described, and

imparts a permanent set to it in its upturned position. Thus the tendency of the flap to droop toward the face of the insole is effectually overcome.

5 The nature and scope of the present invention having been indicated and one form having been specifically described, what is claimed as new is:—

1. As an article of manufacture, a leather blank for insoles, having a flap which is formed by cutting downwardly and outwardly in one face of the blank and which is turned up with the fibers of the leather stretched at its upper margin to produce a length at this portion of the flap greater than the length of the flap at its base to permanently set it, substantially as described.

2. As an article of manufacture, a leather blank for insoles, having a flap which is formed by cutting downwardly and outwardly in one face of the blank and which is turned up and permanently set in its

upturned position by a series of transverse crimps or corrugations throughout its 25 length, substantially as described.

3. As an article of manufacture, a leather blank for insoles, having a flap and a parallel lip cut from one face of the blank and which are turned up and united in 30 their upturned position to form a single substantially upright rib, by a series of co-operating transverse crimps or corrugations throughout its length, substantially as described.

4. As an article of manufacture, a leather insole blank having a marginal lip or rib provided with a series of transverse crimps or corrugations to stiffen it and permanently set it in substantially upright position, substantially as described.

ALBERT E. JOHNSON.
